(57) CLAIM

The ornamental design for a toilet brush, as shown and described.

DESCRIPTION

FIG. 1 is a bottom, front, left side perspective view of a toilet brush.

FIG. 2 is a front elevation view of the brush of FIG. 1.

FIG. 3 is a rear elevation view of the brush of FIG. 1.

FIG. 4 is a left side elevation view of the brush of FIG. 1.

FIG. 5 is a right side elevation view of the brush of FIG. 1.

FIG. 6 is a top plan view of the brush of FIG. 1.

FIG. 7 is a bottom plan view of the brush of FIG. 1; and, FIG. 8 is another perspective view thereof; shown in an environment.

In FIG. 8, the broken lines are for the purpose of illustrating environment only and form no part of the claimed design.
